UNITED STATES PATENT OFFICE.

JOHN M. HOPWOOD, OF DORMONT, PENNSYLVANIA.

COMBUSTION-REGULATING MEANS.

1,400,549.

Specification of Letters Patent. Patented Dec. 20, 1921.

Application filed October 4, 1919. Serial No. 328,563.

To all whom it may concern:

Be it known that I, JOHN M. Hopwood, residing at Dormont, in the county of Allegheny and State of Pennsylvania, a citizen 5 of the United States, have invented or discovered certain new and useful Improvements in Combustion-Regulating Means, of which improvements the following is a specification.

- 10 It is the purpose in employing automatic combustion regulating means to insure an increase in the rate of combustion in case the supply of steam is insufficient and to decrease the rate of combustion when the
- 15 rate of supply is greater than required, or in other words, to regulate combustion so that the rate of generation shall always be proportional to the demand, *i. e.*, shall rise and fall with the demand.
- 20 It is the present practice to connect the motors of the combustion accessories, such as stoking mechanism, blowers, etc., directly to the boiler or to a header connected to all the units of a plant so that the pressure of
- 25 the steam supplied to these accessories will vary with changes of pressure in the boiler or header, except in cases where it is desired to operate the blower at a constant rate, in which case the flow of steam to the
- 30 blower motor is controlled by a governor, and the supply of air to the furnace or furnaces is regulated by a valve or damper. A governor, however, cannot be employed for regulating the flow of steam to the
- 35 stoker engines, as the operation of the latter should vary in accordance with the load in the boiler. In cases where the fan speeds are regulated to suit load requirements, it is the practice to control the flow of steam
- 40 to the fan engine by a valve mechanism, which tends to close the valve when the steam pressure rises and to open the valve when the pressure falls.

Practice has shown that the degree of regulation attained by the employment of such valve mechanism for regulating the operations of stokers, etc., is very unsatisfactory, as no provision is made for compensating for the variation of the pressures 50 of the steam; only the quantity of steam flowing to the stoker and fan engines is varied. Hence although the quantity of steam passed by such valve mechanism will vary as the pressure in the boiler rises or falls, the pressure of the steam so admitted will rise or fall, and only a partial regula-

tion is effected, and experience has shown that as a matter of fact the operations of the stokers and fans do not respond with substantial exactness to changes of load on 60 the boiler, when their engines are directly connected to the boiler or header connected to a plurality of boilers.

The invention described herein has for its object the provision of suitable means whereby the pressure of the steam supplied to the motors of the accessories will not vary with the pressure of the steam supplied by the boiler or boilers, or in other words, it is the object of the invention to supply the 70 motors of the accessories with steam at an unvarying predetermined pressure, so that the operation of the stoker and boiler will respond with substantial exactness to changes of load in the boiler or boilers. The 75 invention is hereinafter more fully described and claimed.

In the accompanying drawing forming a part of this specification is shown diagrammatically a plurality of boiler units with 80 accessories such as fuel feeding means, and means for supplying air for combustion in combination with means for supplying steam at a predetermined and uniform pressure to the motors of such accessories. 85

In the practice of the invention, the boiler is provided with its usual outlet extending to point of use, or to the header 1 forming the outlet for a plurality of boilers, and leading to the engine or other point of use. 90 In order to provide for supplying steam to the accessories at a uniform pressure, an auxiliary header 2 is connected to the boiler or the header 1 through a reducing valve 3 of any suitable construction whereby a uniform pressure may be maintained in the auxiliary header regardless of changes of pressure in the boiler or main header, provided of course that such pressure does not drop below that desired in the auxiliary 100 header. From the auxiliary header, extend connections to the engine 4 of the fan 5 employed for forcing air through the conduit 6, and also to the cylinders of the stoking mechanism, diagrammatically indicated 105 at 7.

It will be readily understood that the improvement described herein can be used in connection with any known system for regulating the feed of fuel and air for combustion 110 whether such system operates to adjust combustion conditions by and in ac-

cordance with changes in pressure of the steam, as shown and described in Letters Patent No. 817438, dated April 10th, 1906, or in accordance with the rate of flow and pressure of steam from the generator to the point or points of use as set forth in Letters Patent No. 1,338,922 granted May 4, 1920, to John M. Hopwood, it being the purpose of this invention to insure that any changes in pressure or rate of flow of the steam shall be followed by changes in the operation of the accessories almost exactly proportional to such changes, and all irregularly acting influences eliminated.

15 I claim herein as my invention:

1. The combination of a steam generator, means for controlling the rate of combustion of fuel in the furnace of said generator, motors for operating said means, connec-

tions from the generator to the motors of 20 said combustion controlling means and means for so regulating the pressure of the steam supplied to the motors that such pressure will not vary with variations of pressure in the generator. 25

2. The combination of a battery of steam generators, a header connected to such battery, means for maintaining a constant pressure of steam in said header, means for controlling the rate of combustion of fuel in 30 the furnaces of said battery, motors for operating said controlling means and connections from said header to the motors of the combustion controlling means.

In testimony whereof, I have hereunto set 35 my hand.

JOHN M. HOPWOOD.
